UNITED STATES PATENT OFFICE.

EDWARD A. HALBLEIB, OF ROCHESTER, NEW YORK, ASSIGNOR TO NORTH EAST ELECTRIC COMPANY, OF ROCHESTER, NEW YORK, A CORPORATION OF NEW YORK.

BRUSH-HOLDER FOR ELECTRIC MOTORS OR GENERATORS.

1,078,194.

Specification of Letters Patent. Patented Nov. 11, 1913.

Application filed November 29, 1912. Serial No. 734,139.

To all whom it may concern:

Be it known that I, EDWARD A. HALBLEIB, a citizen of the United States, and resident of Rochester, in the county of Monroe and 5 State of New York, have invented certain new and useful Improvements in Brush-Holders for Electric Motors or Generators, of which the following is a specification.

This invention relates to brush-holders 10 such as are employed in connection with the commutator-brushes of electric motors or generators of the direct-current type.

The invention relates particularly to brush-holders of the form in which the 15 brush is supported by a pivotally-movable member, which is mounted, either directly or indirectly, upon a supporting-rod fixed on the frame of the motor or generator in a position parallel with the armature-shaft, 20 the supporting-rod constituting an electrical conductor through which connection is made between the brush-holder and other parts of the electric circuit.

The object of the invention is to provide 25 in such a construction a novel and simple arrangement for both securing the supporting-rod removably in place on the frame of the machine, and providing electrical connection between the rod and the conductor 30 or conductors by which the rod, and the brushes supported thereby, are connected with the electrical circuits of the machine.

To the foregoing end the invention consists in the construction hereinafter described, as it is defined in the appended 35 claim.

In the accompanying drawings:—Figure 1 is an end-view, partly in vertical section, 40 of an electric motor or generator provided with brush-holders embodying the present invention; and Fig. 2 is a section on the line 2—2 in Fig. 1.

As the brush-holder constituting the present invention may be employed in connection with any ordinary form of direct-current motor or generator, the drawings illustrate only a portion of the machine in connection with which the brush-holders are used, including one end of the armature 6, 45 the armature-shaft 7, one of the bearings 8 in which the shaft is supported, an end-plate 12 of the casing, and the commutator 9 mounted on the armature-shaft. The brushes 10 are of a well-known arcuate form,

being so supported as to swing toward the 55 commutator in circular arcs concentric with pivotal supports or rods 11. These supports are mounted at their inner and outer ends, respectively, on the end-plate 12 of the motor-casing and on the support 13 by which 60 the shaft-bearing 8 is carried, and they are thus held parallel with the armature-shaft.

Each brush 10 is fixed upon a yoke-shaped brush-carrier having two parallel side-members 14, and a middle-portion 15 which is 65 provided with a cylindrical surface upon which the brush 10 is seated, the brush being fixed in place by means of a clamping-screw 16. The lower ends of the side-members 14 are perforated and provided with 70 bearing-bosses 17, so that the brush-carrier may be pivotally mounted upon one of the rods 11, about which it swings freely.

Near its upper end the brush-carrier has 75 an outward extension formed by a continuation of the side-members and an extension 18 of the middle-portion. This extension 18 is curved inwardly at its outer extremity, forming a lip 19 which is perforated at 80 to receive the outer end of the coiled tension-spring 21 by which the brush-carrier is controlled. The spring 21 is located between the side-members 14 of the brush-carrier, and its inner end is fastened to a spring- 85 supporting arm 22 which has a perforation 23 for this purpose near its upper end. The arm 22 is mounted upon the pivotal support 11 between the side-members 14 of the corresponding brush-carrier, and to prevent rotation of the arm upon the support the 90 support has a longitudinal flattened surface, as shown in Fig. 1, and the arm 22, as shown in Fig. 2, has a perforation so formed as to fit against the flattened surface, thus fixing the arm rigidly against pivotal movement. 95 Accordingly, the spring is subjected to tension between the arm and the brush-carrier, with the result that the brush is held, yielding against the commutator in the usual manner.

When the brush has been worn down to a point at which the tension of the spring has been relaxed to the effective minimum it is desirable that further inward movement of the brush-carrier be arrested, and for this 105 purpose the spring-supporting arm 22 is utilized as a stop, being provided, at its upper end, with a lug or abutment 25 adapt-

ed to engage the middle-portion 15 of the brush-carrier. The rods 11 are utilized as electrical conductors to the brush-carriers and the brushes, and the present invention 5 resides in the simple and effective means employed for the double purpose of removably fixing the rods 11 in place, and at the same time making electrical connection between these rods and the other parts of the machine. As shown in Fig. 2, the inner end of each rod is insulated and supported by means of a bushing 26 in which it is loosely mounted, while the outer end is insulated by a bushing 27. The outer end is also 10 provided with a flat metal arm 28. This arm is pinned or otherwise fastened rigidly to the rod 11, and the outer portion 29 of the arm is reduced in thickness and is secured by means of a binding-post 31, which 15 passes through the arm and through an insulating-bushing in the bearing-support 13, thus serving the double purpose of preventing endwise or rotative movement of the arm and the rod, and of constituting a means 20 of connection with a conductor 31, which extends to the field-winding or any other suitable part of the machine.

Whenever it is necessary to dismount the

brush-holders for any purpose it is necessary only to remove the nut from the binding-post 30, whereupon the rod 11 can be freely withdrawn.

In Fig. 2 the brush-holders are shown as used in pairs upon each side of the commutator, but manifestly they may be used either 35 in greater numbers or singly.

I claim:

In an electric motor or generator, the combination, with a frame-member thereof, of an insulating-bushing therein, a rod 40 mounted loosely in said bushing, a brush-holder supported by the said rod, a rigid arm fixed to and projecting laterally from the rod, and a binding-post connecting said arm and said frame-member, but insulated 45 from the latter, the binding-post normally fixing the arm against movement, and the arm acting both as means to prevent movement of the rod in said bushing, and as an electrical connection between the rod and 50 the binding-post.

EDWARD A. HALBLEIB.
